UNITED STATES PATENT OFFICE

147,559

DESIGN FOR A BADGE

Leo J. Kelly, Chicago, Ill., assignor to National Sanitary Supply Association, Chicago, Ill., a corporation of Michigan

Application July 30, 1945, Serial No. 121,061

Term of patent 14 years

(Cl. D29—2)

To all whom it may concern:

Be it known that I, Leo J. Kelly, a citizen of the United States and a resident of Chicago, in the county of Cook and State of Illinois, have invented a new, original, and ornamental Design for a Badge, of which the following is a specification, reference being had to the accompanying drawing, forming a part thereof, and in which:

Fig. 1 is a front elevational view of a badge showing my new design;

Fig. 2 is a side elevational view of the same.

I claim:

The ornamental design for a badge, as shown.

LEO J. KELLY.
